AUTOMATIC IGNITION-SWITCH.

1,359,688.

Specification of Letters Patent. Patented Nov. 23, 1920.

Application filed March 7, 1918. Serial No. 221,067.

To all whom it may concern:

Be it known that I, VALÈRE A. FYNNE, a subject of the King of England, residing at the city of St. Louis, State of Missouri, 5 United States of America, have invented a certain new and useful Automatic Ignition-Switch, of which the following is such a full, clear, and exact description as will enable any one skilled in the art to which it 10 appertains to make and use the same, reference being had to the accompanying drawings, forming part of this specification.

My invention relates to battery ignition systems, and in particular to a system in 15 which the primary ignition circuit is normally closed.

In systems of the type above referred to it is desirable to employ means to prevent over-heating the spark coil and unnecessarily draining and possibly entirely discharging the battery, if the operator omits to open the ignition switch after the engine has come to rest and the timer has stopped in its closed position. The battery and coil 20 protecting means herein described comprise a centrifugal switch combined with another ignition switch, adapted to shunt the former during the starting operation and so arranged as to automatically open as soon as 25 the centrifugal switch has closed. I prefer to combine this auxiliary automatic switch with the usual hand operated ignition switch.

In the accompanying drawings, Figure 1 30 shows one embodiment of my invention, while Fig. 2 is a modification thereof.

Referring to Fig. 1, the high tension winding of the spark coil 3 is grounded at one end and connected to a distributor 30 at the other. This distributor is connected to the spark plugs 34 in the usual way. One pole of the primary of the spark coil is connected to the stationary contact 7 of the centrifugal switch, through the storage battery 2, while the other pole of said winding is connected to the levers 18 and 27 of the automatic ignition switch, through the timer 28, 29. The stationary contact 9 of the centrifugal switch is connected to the contact 35 17, coöperating with the lever 18, and the stationary contact 8 of the centrifugal switch is connected to the negative pole of the battery 2 through the electromagnet 10. The centrifugal switch is mounted on the 40 shaft 4, provided with a pulley 6 adapted to be driven from the engine. The movable

contact 32 of this switch is under the control of the weights 5 and is adapted to move longitudinally along the shaft 4 and to co-operate with the stationary contacts 7, 8 and 9. The cam 29 of the timer and the distributor 30 are driven from the engine in the usual way.

The automatic ignition switch comprises the two levers 18 and 27, both pivoted at 35 and in electrical contact with each other. The spring 23 tends to keep the lever 27 against the stop 19 on the lever 18 and the spring 20 attached to the projection 33 of the lever 18 tends to keep both levers in their 40 off position, in which the lever 27 rests against the stop 16. Both levers may be moved by means of the handle 36. The counter-clockwise rotation of the lever 27 is arrested by the catch 14 mounted on the flat 45 spring 11 held in the clamp 12 and carrying an armature 13, adapted to coöperate with the electromagnet 10. As long as the catch 14 is in the control of spring 11, it will prevent the lever 27 from moving in a counter-clockwise direction beyond that point in 50 which it rests on the stationary contact 15, which is connected to the positive pole of the battery 2 through the electromagnet 25. When this electromagnet 10 takes control of 55 the catch 14, then the lever 27 is free to move beyond the contact 15. The lever 18 is adapted to be held in its position of contact with the terminal 17 by means of the spring 60 controlled catch 22, coöperating with the 65 notch 21 in said lever. The spring carrying the catch 22 is held at 24 and carries an armature 26 coöperating with the electromagnet 25. When this electromagnet is 70 energized, the catch 22 is rendered inoperative, as shown in Fig. 1.

The operation of the arrangement shown in Fig. 1 is as follows: With the engine at rest, the centrifugal switch will be open, as shown in the figure. The catch 14 will be 75 under the control of the spring 11 and stands in the way of the lever 27. The catch 22 will be under the control of its spring and ready to arrest the travel of the lever 18. The position of the timer and of the distributor is 80 determined by the position in which the engine came to rest and is immaterial. The automatic ignition switch is under the control of the spring 20, the lever 27 resting against the stop 6 and the lever 18 resting 85 against the lever 27 at 19. The engine may be started in any desired manner, but

while it is being cranked, the automatic ignition switch should be turned in a counter-clockwise direction by means of the handle 36 and preferably until the lever 18 comes into contact with the terminal 17. The two levers 18 and 27 being held together by the spring 23 will at first move without change in their relative position, but as soon as the lever 27 rests on the contact 15 its further movement will be arrested by the catch 14 and any further movement of the lever 18 will place the spring 23 under tension. Contact between the lever 27 and the terminal 15 shunts the centrifugal ignition switch 32 and also the hand operated switch 17, 18 and connects the positive pole of the battery 2 to one end of the low tension winding of the spark coil through the electromagnet 25 and the timer 28, 29. The energizing of the electromagnet 25 will place the catch 22 under the control of the latter and render said catch inoperative. For this reason, the hand ignition switch must be held in its closed position against the springs 20 and 23 until the engine has fired. Should the engine fail to start, then levers 27 and 18 will fly back to their first off position as soon as released, but if the engine fires and equals or exceeds its lowest operating speed, then the centrifugal switch will interconnect the stationary contacts 7, 8 and 9. As soon as the contact 8 is connected to contact 7, the electromagnet 10 will be energized, attracting the armature 13, yielding the lever 27 to the control of the spring 23 and interrupting the circuit of the electromagnet 25 at the point 15. The demagnetization of 25 releases the catch 22 which engages with the notch 21 as shown in Fig. 2 and holds the lever 18 in its closed position independently of the operator, who can then release the handle 36.

The centrifugal switch is so set that it will connect the contacts 7 and 8 at, or near the lowest operating speed of the engine and disconnect them at a considerably lower speed. It may sometimes be desired to have the movable contact 32 connect the stationary contacts 7 and 9 before connecting the contacts 7 and 8 as shown in Fig. 1. As the engine speed increases and the contact 32 moves farther along the shaft 4, it interrupts the circuit of the electromagnet 10 at the point 8, thus allowing the catch 14 to resume its normal position and reducing the drain on the battery. Should the engine now come to rest, the centrifugal switch will interrupt the ignition circuit at the points 7 and 9 and prevent the battery from discharging through the primary of the spark coil, even though the ignition switch 18 is still held in its closed position by means of the catch 22. Before the engine can be again started, it is necessary to first return the levers 18 and 27 to their off position.

The catch 14 is so formed as not to hinder this movement. This can be done by overcoming the resistance of the catch 22 by means of the handle 36 or by temporarily closing the circuit of the electromagnet 25 independently of the lever 27 and by means of the spring controlled switch 37. After the hand controlled ignition switch has been returned to its off position, the operations just described can be repeated, the engine being cranked by hand or by means of a cranking motor as is now usual.

One way to interrupt the ignition while the engine is running is to forcibly overcome the resistance of the catch 22 and return the levers 18 and 27 to their off positions. The resistance of the catch 22 may be overcome either by putting extra pressure on the handle 36 or by moving the catch itself out of the way by hand, or by temporarily closing the switch 37 energizing the electromagnet 25. In order to reinstate ignition under the same conditions, the lever 18 should be brought back into its closed position. In so doing, the lever 27 may be arrested in the position shown in Fig. 1 in case contact between 32 and 8 is broken at the time. If so arrested, then 18 will not remain in its closed position. In order to overcome this difficulty, all that is necessary is to make the contact 8 as long as the contacts 7 and 9, thus keeping the electromagnet 10 energized as long as the engine is in operation. As an alternative, the low tension ignition circuit may be temporarily interrupted for the purpose stated, at any desired point and independently of the hand controlled ignition switch.

Referring to the modification shown in Fig. 2 it differs from Fig. 1 only in that the electromagnet 10 is here included in the primary ignition circuit itself between the stationary contact 7 of the centrifugal switch and the positive pole of the battery 2, instead of being adapted to be connected to the terminals of the battery and in shunt with the primary ignition circuit. The contact 8 of Fig. 2 is connected to short-circuit the electromagnet 10 when the centrifugal ignition switch closes. In order to achieve the result obtained in Fig. 1, by making the contact 8 of said figure as long as the contact 7 thereof for the purpose of keeping the electromagnet 10 energized as long as the centrifugal switch is closed, it is only necessary in Fig. 2 to omit the contact 8 altogether. The operation of the arrangement shown in Fig. 2 is identical with that shown in Fig. 1. During the starting operation, the hand controlled ignition switch is held in the position shown in Fig. 2. Under these conditions, the electromagnet 25 is energized and the catch 22 does not coöperate with the notch 21. As soon as the centrifugal switch closes, the electromagnet 10 is energized,

the lever 27 released, the electromagnet 25 demagnetized and the lever 18 locked in the position shown, by means of the catch 22. If the contact 8 of Fig. 2 is made use of, 5 then upon a certain increase in the engine speed, the electromagnet 10 is short-circuited at the points 7 and 8 and the resistance of the primary ignition circuit is accordingly reduced. This reduction is, however, very 10 immaterial, because the electromagnet 10 need only be small and can readily be designed to offer but a small impedance to the ignition current.

Having fully described my invention, 15 what I claim as new and desire to secure by Letters Patent of the United States is:

1. In an ignition system for internal combustion engines, an ignition circuit comprising a source of current, a timer and a 20 controlling switch, means for establishing a circuit in shunt with said switch, and means governed by the speed of the engine for opening the shunt circuit.

2. In an ignition system for internal combustion engines, an ignition circuit comprising a timer, a source of current and a switch controlled by the speed of the engine for opening and closing said circuit, means for establishing a circuit in shunt with said 25 switch, and means governed by the switch for opening said shunt circuit.

3. In an ignition system for internal combustion engines, an ignition circuit comprising a timer, a source of current and a switch 30 controlled by the speed of the engine and open when the engine is at rest, means for establishing a circuit in shunt with said switch, and means governed by the switch for closing the ignition circuit at one engine 35 speed and opening said shunt circuit at a higher speed.

4. In an ignition system for internal combustion engines, an ignition circuit comprising a timer, a source of current and a switch 40 controlled by the speed of the engine for opening and closing said circuit, a manually operable switch for establishing a circuit in shunt with the speed controlled switch, means holding the manual switch in closed 45 position, and means governed by the speed controlled switch for releasing the manual switch.

5. In an ignition system for internal combustion engines, an ignition circuit comprising a timer, a source of current and a controlling switch, a switch for establishing a circuit in shunt with said controlling switch, and electromagnetically controlled means 55 for holding said switch in closed position.

6. In an ignition system for internal combustion engines, an ignition circuit comprising a timer, a source of current and a controlling switch, a switch for establishing a circuit in shunt with said controlling switch, 60 electromagnetically controlled means for

holding said switch in closed position, said electromagnetic means being governed by the controlling switch.

7. In an ignition system for internal combustion engines, an ignition circuit comprising a source of current, a timer, a controlling switch governed by the speed of the engine and a manually operable switch, a second manually operable switch for establishing a circuit in shunt with said ignition 75 switches, and means governed by the speed controlled switch for releasing said second manually operable switch.

8. In an ignition system for internal combustion engines, an ignition circuit comprising a source of current, a timer, a controlling switch governed by the speed of the engine and a manually operable switch, and electromagnetically controlled means for holding the manual switch in closed position, said means being governed by the speed controlled switch.

9. In an ignition system for internal combustion engines, an ignition circuit comprising a source of current, a timer, a controlling switch governed by the speed of the engine and a manually operable switch, and means controlled by the manually operable switch for establishing a circuit in shunt with the speed controlled switch.

10. In an ignition system for internal combustion engines, an ignition circuit comprising a source of current, a timer, a controlling switch governed by the speed of the engine and a manually operable switch, means for establishing a circuit in shunt with said ignition switches, and means governed by the shunt circuit for holding the manual switch in closed position.

11. In an ignition system for internal combustion engines, an ignition circuit comprising a source of current, a timer, a controlling switch governed by the speed of the engine and a manually operable switch, a second manually operable switch for establishing a circuit in shunt with the said ignition switches, and resilient means connecting the said manually operable switches.

12. In an ignition system for internal combustion engines, an ignition circuit comprising a source of current, a timer, a controlling switch governed by the speed of the engine and a manually operable switch, a second manually operable switch for establishing a circuit in shunt with the said ignition switches, resilient means connecting the said manually operable switches and tending to bring the second switch to open position when the first switch is closed, and means for holding said second switch in closed 125 position.

In testimony whereof, I have hereunto set my hand and affixed my seal.

VALÈRE A. FYNN. [L.S.]
